ATTORNEY

UNITED STATES PATENT OFFICE.

CHARLES HARDY, OF NEW YORK, N. Y., ASSIGNOR TO AMSCO PRODUCTS, INC., OF NEW YORK, N. Y., A CORPORATION OF NEW YORK.

MULTIPLE-PURPOSE RHEOSTAT.

Application filed July 11, 1924. Serial No. 725,361.

To all whom it may concern:

Be it known that I, CHARLES HARDY, a citizen of the United States, and a resident of New York, in the county of New York 5 and State of New York, have invented certain new and useful Improvements in Multiple-Purpose Rheostats, of which the following is a specification.

My invention relates to multiple purpose 10 rheostats, of the type in which a number of separate resistance elements are controllable independently of each other, for the purpose of varying the resistance in different circuits and thus regulating the current values of the 15 different circuits.

An object of the invention is to produce a multiple purpose rheostat of compact form and simple construction, and made up essentially of a number of separate rheostats 20 grouped compactly together, the different rheostats having separate knobs or equivalent handles whereby they may be controlled independently of each other.

A further object is to provide simple 25 and efficient means for insuring proper mechanical and electrical engagement between the several parts.

Other objects and aims of the invention, more or less specific than those referred to 30 above, will be in part obvious and in part pointed out in the course of the following description of the elements, combinations, arrangements of parts and applications of principles, constituting the invention, and 35 the scope of protection contemplated will be indicated in the appended claims.

In the accompanying drawings which are 40 to be taken as a part of this specification, and in which I have shown merely a preferred form of embodiment of the invention:—

Fig. 1 is a horizontal section through my 45 multiple purpose rheostat, showing the same as mounted upon a supporting panel, and

Fig. 2 is a front elevation of the multiple 50 purpose rheostat and parts immediately associated therewith including a diagrammatic illustration of a set of circuits connected to be controlled by the present device.

A panel board 3 is used for supporting the various parts, and may be the wall of a radio cabinet, or of any other appropriate casing.

Extending through a hole in the panel

board 3, and revoluble relatively to the panel board, is a metallic sleeve 4 of substantially cylindrical form, provided with a flange 5. This flange is integral with the sleeve 4, and thus is revoluble relatively to 60 the panel board.

A body member 6, of substantially circular form, is mounted upon the panel board 3 by any suitable retaining means as for instance one or more bolts 7. 65

The body member 6 carries resistance strips 8 and 9. These resistance strips are each of arcuate form, and they are disposed concentrically to each other and to the circular body 6, as may be understood from Fig. 2. The strip 8 is of greater cross diameter than the strip 9, and may carry more current than the strip 9.

Mounted upon the body member 6 are binding posts 10, 11 and 12. While the number of resistance strips 8 and 9 and the number of the binding posts 10, 11 and 12 can be varied to suit requirements, I show in the present instance only two resistance strips and three binding posts. The strip 8 is 80 connected with the binding post 10 and the strip 9 is connected with the binding post 11. The binding post 12 is for ground connection, that is it carries the opposite side of the circuit from posts 10 and 11. 85

Secured rigidly upon the revoluble sleeve 4, and retained against displacement relatively thereto, as by a nut 14, is a contact arm 13 which extends radially outward and slidably engages the resistance strip 9. 90

Another contact arm 15 is mounted upon a set collar 16, the latter being secured rigidly upon a revoluble shaft 17 which extends through the sleeve 4. The outer end of the contact arm 15 rests upon and is slidable 95 along the resistance strip 8.

An operating knob 18, preferably of insulating material and having a tubular metallic core 19, is mounted upon the sleeve 4 and is held in position thereupon preferably by a set screw 20. The knob 18 is revoluble by hand, so that the operator, by turning it, rotates the sleeve 4 and thus actuates the contact arm 13. 100

A second operating knob 21 is mounted rigidly upon the outer end of the shaft 17, and is revoluble by hand for enabling the operator to rotate this shaft and so actuate the contact arm 15.

Thus the operator, by grasping and turn- 110

ing either of the knobs 18 or 21, can cause the rotation of the corresponding contact arm 13 or 15 independently of each other.

The resistance strip 8 is shown as being somewhat higher than the strip 9 so that the contact arm 15 can span directly over the strip 9 and into contact with the strip 8. This facilitates compactness of the parts.

Although it is herein above suggested that 10 the resistance strips 8 and 9 may be of different capacities, it will be nevertheless understood that they may be of substantially identical capacities if desired, according to the work which it is intended the individual 15 strips shall perform.

The binding post 22 is connected electrically with both the sleeve 4 and the shaft 17 by means of a connecting link 12 which extends from said binding post 12 to a position beneath the flange 5 of the sleeve. The spring pressure of the contact arm 13 against the resistance strip 9 tends always to move the sleeve longitudinally and thus produces a resilient pressure of the flange 5 against 25 the underlying portion of link 22. The spring pressure of the contact arm 15 against the resistance strip 8 also produces a continuous pressure of the shaft 16 laterally against the inner wall surface of the 30 sleeve 4 and thus provides a good electrical contact between said shaft and sleeve. The knob 21 at the front end of the shaft 17 of course holds said shaft against longitudinal movement.

35 One or more appropriate electric circuits may be connected with my device by means of the binding posts 10, 11 and 12, and in Fig. 2 I show diagrammatically a very simple example of such circuits. A wire 23 is connected with the binding post 12 and with a battery 24. In metallic communication with this battery are two wires 25 and 26, leading to incandescent lamps 27 and 28 respectively adapted to be energized by 40 currents from the battery 24.

45 From the lamp 27 a wire 29 leads to the binding post 10, and from the lamp 28 a wire 30 leads to the binding post 11. Vacuum tubes or any other appropriate elements may be substituted for the lamps 27 and 28.

50 The contact arm 13 is included in the circuit through the lamp 28, and the contact arm 15 is included in the circuit through the lamp 27.

55 With the apparatus thus arranged the operator, by turning the knob 21 and actuating the contact arm 15, can regulate the current passing through the lamp 27; and by turning the knob 18 and thus actuating the contact arm 13, he can control the current through the lamp 28.

60 My multiple purpose rheostat is well adapted for radio work such as the reception of broadcasted performances, etc. In

this relation it may be used for controlling the various delicate circuits used, for instance in second stage audio and second stage radio frequency, or otherwise as may be desired.

70 In instances where only two circuits are to be controlled, one of these can be a radio frequency circuit and the other an audio frequency circuit, and this is true whether the circuits be of the first stage or the second stage, or any higher stage, of amplification. However, the various kinds of circuits to be controlled may be very numerous and I make no effort to suggest all of the ways in which 75 they may be controlled by means of my invention.

80 As many changes could be made in this construction without departing from the scope of the invention as defined in the following claims, it is intended that all matter contained in the above description or shown in the accompanying drawings, shall be interpreted as illustrative only and not in a limiting sense.

85 I claim:

90 1. A multiple purpose rheostat comprising a body member of insulating material, a metallic sleeve extending through said body member and revolvable therein, an operating handle fixed to said sleeve at one side of the body member by which to rotate the sleeve, said sleeve having a shoulder thereon at said mentioned side of the body member facing toward the opposite side of the body member, a resistance strip carried by the body 100 member at said opposite side thereof, a contact arm carried by said sleeve arranged to sweep along said resistance strip by rotation of the sleeve, said contact arm being of spring material and being under tension exerting a pressure in a direction toward said first side of the body member against the resistance strip and a resultant pressure tending to move the sleeve longitudinally through the body member and thereby pressing the 105 flange of the sleeve toward said first side of the body member, a binding post carried by the body member, a conductor member extending from said binding post into position between the body member and the opposing 110 surface of the flange of the sleeve to receive frictional contact therefrom during rotation of the sleeve, a second resistance strip carried by the body member at the same side of the body member as said first resistance 115 strip, a metallic shaft extending through the sleeve and revolvable therein, an operating handle fixed to the shaft beyond one end of the sleeve adjacent said first operating handle, a contact arm fixed to the shaft beyond 120 the opposite end of the sleeve arranged to sweep along the second resistance strip upon rotation of the shaft, said second contact arm being also of spring material and being under tension exerting a pressure toward the 125 130

first mentioned side of the body member against the second resistance strip and a resultant pressure serving to hold the shaft laterally in tight rubbing contact with the inner surface of the sleeve whereby the mentioned binding post is electrically connected in common with both of said contact arms, and a pair of other binding posts carried by the body electrically connected with said resistance strips respectively.

2. A multiple purpose rheostat comprising a body member of insulating material having a bearing opening therethrough from its front to its rear surface and having an annular groove formed in its rear surface spaced concentrically from said bearing opening, a plurality of resistance strips arranged within said groove extending longitudinally along the groove and hence concentrically about said bearing opening, retaining means also within said groove arranged between said strips and serving to hold said strips spaced apart and to retain said strips against displacement from the groove, each of said strips having a longitudinally extending exposed surface portion thereof facing rearwardly outwardly of the groove, one of said resistance strips having its mentioned surface arranged relatively further rearwardly than the mentioned surface of another resistance strip, a plurality of operating members mounted to rotate within said bearing opening, a contact arm carried by one of said members arranged upon rotation of said member to sweep along the mentioned exposed surface of one of said resistance strips, and a further contact arm carried by another of said operating members projecting therefrom across said last mentioned resistance strip free thereof and arranged thereby to sweep along the mentioned exposed surface which is dis-

posed rearwardly of the exposed surface of the last mentioned strip.

3. A multiple purpose rheostat comprising a body member of insulating material having a bearing opening therethrough from its front to its rear surface and having an annular groove formed in its rear surface spaced concentrically from said bearing opening, a pair of resistance strips arranged within said groove extending longitudinally along the groove and hence concentrically about said bearing opening, a retaining strip also within said groove arranged between said strips and serving to hold said strips spaced apart and pressed radially against the walls of the groove to thereby retain said strips against displacement from the groove, the groove being of uniform depth throughout, the resistance strips projecting rearwardly from said groove but being of different cross sectional dimensions so that one thereof projects further rearwardly from the groove than the other, the rear annular edge surfaces of said strips constituting contact surfaces and being thus disposed in different planes longitudinally of said bearing opening, a pair of operating members mounted to rotate within said bearing opening, a contact arm carried by one of said members arranged upon rotation of said member to sweep along the mentioned exposed surface of one of said resistance strips, and a further contact arm carried by the other of said operating members projecting therefrom across said last mentioned resistance strip free thereof and arranged thereby to sweep along the contact surface of the resistance strip which projects farthest from the groove.

In testimony whereof I affix my signature.

CHARLES HARDY.
